UNITED STATES PATENT OFFICE.

EDWARD L. KINAST, OF CHICAGO, ILLINOIS.

SCORING ATTACHMENT FOR PRINTING-PRESSES.

1,144,139.

Specification of Letters Patent. Patented June 22, 1915.

Application filed July 9, 1913. Serial No. 778,014.

To all whom it may concern:

Be it known that I, EDWARD L. KINAST, a citizen of the United States, residing at Chicago, in the county of Cook and State of Illinois, have invented certain new and useful Improvements in Scoring Attachments for Printing-Presses, of which the following is a description.

My invention belongs to that general class 10 of devices known as scoring attachments for use on printing presses, and relates particularly to a combined scorer and gripper, or frisket finger.

The invention has among its objects the 15 production of a device of the kind described that is simple, convenient, efficient, durable, adjustable and satisfactory, and that may be used wherever found applicable.

To this end my invention consists in the 20 novel construction, arrangement and combination of parts herein shown and described, and more particularly pointed out in the claims.

In the drawings, wherein like reference 25 characters indicate like or corresponding parts, Figure 1 is a view in elevation of the device, and a portion of the rocking gripper bar. Fig. 2 is substantially a side elevation of the same. Fig. 3 is a cross sectional view 30 taken substantially on line 3, 3 of Fig. 2. Fig. 4 is a similar sectional view showing the same in an adjusted position. Fig. 5 is a cross sectional view of a portion of the same reversed, and Fig. 6 is a sectional view 35 of a modified form.

Referring to the drawings, in which the preferred form of my device is shown, it may be mentioned that the device consists in a combined scorer and gripper finger, which 40 may be reversed and used as a sheet gripper or frisket finger only, if it is so desired. The device is attached to the usual rocking bar or gripper finger bar 1, which is suitably secured to the printing press and operated 45 in any desired manner. Detachably and adjustably secured to the bar 1 is the finger 2, preferably provided with an enlarged and flattened end 3, adapted to be positioned on the bar 1. The finger is secured to the bar by 50 a bolt 5 and nut 4, or equivalent means, the bolt preferably extending through a slot in the bar 1. In order to prevent the finger end from moving transversely, or that is, its pivoting on the bolt, the slot 7 is arranged 55 in the bar and the finger end 3 provided with a flange 6, which is adapted to be posi-

tioned therein. The device shown is also preferably provided with an oppositely extending lateral flange 8, adapted to fit into the slot 7 when the bar is reversed, as is 60 hereafter described.

Upon one face or side of the finger 2 is a scoring ridge or bead 9, which is brought to an edge of the desired degree of sharpness. The finger is also provided on the opposite 65 face or side with a detachable part 10, the same being secured in place by screws 11, or the equivalents for the purpose. When it is desired to increase the thickness of the finger, the part 10 may be separated and any 70 desired number of sheets of paper, wood or metal 12, or the equivalent, inserted between the two parts. The number of sheets, of course, depends upon the thickness of the same and the desired thickness of the finger, 75 the desired thickness of the finger, of course, depending upon the depth or degree of scoring which is required or desirable. In the modified construction shown in Fig. 6, the detachable back 15 is provided with a groove 80 17, corresponding in contour with the bead 9, so that when part 2 is turned around and the screws 16 tightened down, the finger is reduced in thickness the depth of the bead 9, and may be used as a gripper only. 85

In operation, assuming that the device is in the position as shown, when the platen is moved up to the bed the scorer carried by the gripper bar is positioned between the two, and the bead or ridge 9 is impressed 90 into the paper, whether it may be light or heavy cardboard stock or the like. (I have not considered it necessary to illustrate the platen and bed of the press, as these parts are well known to those skilled in the art, 95 and the operation of the press is familiar to all.) The scoring finger may be moved along the bar 1 so as to score at any desired point. If it is not desired to use the scorer, the back part 10 may be detached and the 100 finger 2 reversed or turned around, for example, as indicated in Fig. 5, so that the flange 8 engages in the groove 7. By removing the detachable back, the thickness of the scorer is so reduced that there is no scoring 105 of the paper. With a scoring device of this kind it will be noted that there is no printing of the scorer upon the material, since the scorer is never inked when the type is inked, as is the case where a scorer is carried 110 by the bed. The scorer may be increased or decreased in thicknesses by adding or re-

moving paper between the two parts, so as to score the desired depth, depending upon the material in the press. The device is exceedingly simple, in fact so simple that it 5 cannot possibly get out of order, nor does it require extensive time to adjust it, either in its position on the press or as to depth of scoring.

Having thus described my invention, it is 10 obvious that various immaterial modifications may be made in the same without departing from the spirit of my invention; hence I do not wish to be understood as limiting myself to the exact form, construction, arrangement or combination of parts 15 herein shown and described, or uses mentioned.

What I claim as new and desire to secure by Letters Patent is:—

- 20 1. A device of the kind described, comprising the combination of a finger adapted to be secured at one end to the rocking bar, and provided with a ridge on one face thereof with a coöperating back plate formed to 25 lie upon the opposite face of the finger, and means for detachably securing the same together.
2. A device of the kind described, comprising a finger bar constructed with a V- 30 shaped extension on one face thereof, and arranged to be detachably connected to a rocking shaft, in combination with a coöperating back plate, provided with a groove

adapted to receive the ridge when the bar is reversed, and means for detachably securing the two together. 35

3. In a device of the kind described, a rock shaft provided with a longitudinal adjusting slot and a groove for receiving an extension on the coöperating finger, in combination with a coöperating finger, provided at one end with a T-shaped extension constructed on either side to be set in the groove and a bolt hole therethrough, one face of the finger being provided with a V-shaped ridge 40 a coöperating back plate adapted to lie against the opposite face of the finger, and means for detachably securing the two together. 45

4. A device of the kind described, comprising a finger bar constructed at one end with a T-shaped head and a bolt hole therethrough, and provided a V-shaped ridge on one face thereof, in combination with a coöperating back plate constructed with a slot 50 adapted to receive the V-shaped ridge when the finger bar is reversed, and means for 55 securing the two together.

In testimony whereof, I have hereunto signed my name in the presence of two subscribing witnesses.

EDWARD L. KINAST.
